DESIGN FOR A TEXTILE FABRIC OR SIMILAR ARTICLE

Robert Finkelstein, Woonsocket, R. I.

Application April 18, 1940, Serial No. 91,755

Term of patent 3½ years

To all whom it may concern:

Be it known that I, Robert Finkelstein, a citizen of the United States, residing at Woonsocket, in the county of Providence and State of Rhode Island, have invented a certain new, original, and ornamental Design for a Textile Fabric or Similar Article, of which the following is a specification, reference being had to the accompanying drawing, forming a part thereof.

The figure is a plan view of a section of the textile fabric or similar article on which appears all of the characters, designs and printed matter comprising my design, continuations of the fabric being duplications of the matter shown.

I claim:

The ornamental design for a textile fabric or similar article, substantially as shown.

ROBERT FINKELSTEIN.
